UNITED STATES PATENT OFFICE.

THOMAS SPENCER, OF WESTBROOK, CONNECTICUT.

SYSTEM OF ELECTRIC DISTRIBUTION.

SPECIFICATION forming part of Letters Patent No. 378,738, dated February 28, 1888.

Application filed August 13, 1887. Serial No. 246,879. (No model.)

To all whom it may concern:

Be it known that I, THOMAS SPENCER, a citizen of the United States, residing at Westbrook, in the county of Middlesex and State of Connecticut, have invented certain new and useful Improvements in Systems of Electric Distribution, of which the following is a specification.

In electric-lightsystems now in use, and particularly in those employing the Edison three-wire system, it is the custom to connect the light-mains at different points to a number of conductors called "feeders," led from the central station, for the purpose of maintaining the electro-motive force constant on the main. Such an arrangement would be effectual if the feeders always carried the current for which they are calculated. In systems, however, where the "consumer" is enabled to cut in or out his own lamp at will a varying number of lamps are in circuit, and the consequent variation of resistance of the main renders it necessary to use some equalizing device, so that each feeder will carry the proper current. For this purpose, ordinarily, rheostats, called in this connection "feeder regulators" or "equalizers," are employed, placed in the feeders at the station. Such equalizers, however, require constant watching and care to perform their service, and my improvement relates to a system of distribution wherein such equalizers are done away with.

My improvement consists in the combination, with such a system of mains having a plurality of feeding-points, of one or more wires connecting the mains at the feeding-points independent of the feeders and not employed to tap lights from.

My invention will be described with reference to the accompanying drawings, in which—

Figure I represents diagrammatically an electric-light system as customarily arranged. Fig. II is a similar view showing my improvement. Fig. III is a similar view of a modified form of the latter.

Referring to Fig. I, it will be seen that the

light-mains *x* are arranged in the form of a net-work, supplied with current by feeders *y* from dynamos *c* at the central station. The feeders are connected to the main at *a a' a''*, 5c and are provided with rheostats *e' e''*, &c., for the purpose stated.

In Fig. II, illustrating my system, the rheostats are omitted, and the feeding-points *a a' a''* are connected by wires *A* of low resistance. 55 The form shown in Fig. III is somewhat like that of Fig. II; but as it is not necessary for all the feeders to run to the central station I here show a simple set of wires, *b*, running from the station and supplying all the feeders. 6c

It will be seen that with either of the arrangements shown in Figs. II and III, should any feeder have any different electro-motive force from the others, a current is immediately set up in the wires *A*, called by me "equalizers," and the electro-motive force is at once equalized at the feeding-points. 65

It is plain that, although I have here shown my invention applied to an Edison three-wire system, it is equally applicable to higher orders of compensating systems or to simple systems using but two wires. 70

Having thus described my invention, the following is what I claim as new therein and desire to secure by Letters Patent: 75

1. In a system of electric distribution, the combination, with mains having a plurality of feeding-points and feeders, of low-resistance equalizing-conductors independent of the feeders and connecting the mains at the feeding-points, substantially as set forth. 80

2. The combination of a central station, electric-light mains, a plurality of feeders connecting said station with different points on said mains, and equalizing-conductors independent 85 of the feeders and connecting the mains at the feeding-points, substantially as set forth.

THOMAS SPENCER.
